DRYING APPARATUS

Ernest J. Sweetland, Piedmont, Calif.

Application March 27, 1934, Serial No. 717,583

9 Claims. (Cl. 34—26)

This invention relates to a drying apparatus and particularly to apparatus adapted for drying plaster casts as they are applied to the human body for surgical purposes.

It is common practice to apply plaster casts to the human body to hold parts thereof in place during the knitting of broken bones and for other purposes. Frequently such casts, in cases of broken backs, broken hips and the like, are large enough to enclose the major portion of the trunk and lower limbs of the body. In such instances the question of drying the cast is a serious one for several reasons. Patients frequently contract pneumonia from long continued contact with the wet plaster cast. Not only are such casts extremely uncomfortable while they are wet but the coolness produced by evaporation tends to reduce body temperature at a time when the patient's resistance is low due to shock, loss of blood, etc. and it is therefore important to warm and dry the entire cast with the least possible delay after it is applied. Another difficulty that is commonly encountered is that the cast does not attain its full strength until it is substantially dry and they are frequently broken while the patient is being moved in the wet cast.

The customary method for drying plaster casts at present in use is by means of electric lamps and similar heating devices which are brought in proximity with a portion of the cast at a time. Such methods are unscientific and unsatisfactory because extreme vigilance is necessary to avoid allowing the cast to become overheated in spots, thus causing discomfort or actual injury to the patient. Furthermore, such methods necessitate drying only a portion of the cast at a time, under which circumstances it is impossible to make the patient comfortably warm at all parts of the body, and it has the further objection that the patient must be moved to several different positions before complete drying can be effected. Moving and turning the patient over under these circumstances frequently causes great pain and actual danger of increasing his injury.

The object of my invention is to provide a method and apparatus for drying plaster casts promptly and uniformly without danger to the patient and without the necessity of moving the patient's body during the entire drying operation. My method requires from two to five hours for complete and satisfactory drying whereas the methods at present in use usually require from 24 to 48 hours to attain the same degree of dryness.

A further object of the invention is to provide

uniform means of increasing the body temperature. Also I provide means for quickly reducing the temperature if required for the patient's comfort.

To accomplish the objects of my invention I employ a certain apparatus illustrated in detail in the accompanying drawing.

Referring to the drawing:

Figure 1 represents an elevation partially in section showing the apparatus in operation. 10

Figure 2 is a fragmentary sectional view taken on the lines II—II of Figure 1.

Figure 3 is a plan view showing a portion of the apparatus in section.

Figure 4 is a sectional elevation of one of the 15 nozzles showing means of securing the nozzles in operative position.

Figure 5 shows a modification of my invention wherein felt spacing members may be used in certain cases as a substitute for the wire mat. 20

Figure 6 is a modification wherein a sheet is secured to each side of the metallic mat.

Referring to the drawing in detail, 1 indicates a bed upon which is mounted the customary mattress 2 and springs 3. 4 diagrammatically indicates a cross section of the human body which is surrounded by the plaster cast 5. Surrounding the cast 5 is the coiled spring mat 6 and this in turn is surrounded by the sheet 7, which sheet is reinforced longitudinally by a plurality of stays 8 which are held in place by rows of stitching which form pockets between the two layers of fabric of which the sheet 7 is composed. The stays 8 are preferably made of stainless spring steel, although they may be made of thin strips of wood or any suitable material which tends to stiffen the sheet longitudinally while permitting lateral flexibility. These stays are of thin spring material which permits a reasonable amount of longitudinal flexibility so that the sheet may conform to the indentations formed in the mattress by the contour of the body. The sheet 7 may be of canvas or any flexible material which does not permit air to pass through it freely. 9 is a nozzle which is flattened at its delivery end so as to 45 distribute the air stream delivered through the tubes 11. 10 is a loose plate of sheet metal which may be used to direct the streams of air and prevent them from being dissipated before they are well started through the channels of the mat. If 50 desired to reverse the flow of air currents so that they enter at the top of the cast and discharge from the bottom side, this plate is then inserted between the springs 6 and the top of the cast and the position of the nozzles changed accordingly. 55

12 represents an air blower which is operated by a motor of conventional design which is contained in the casing 13 (Figure 3). On the intake side of the blower is a funnel-shaped housing 14 within which is mounted a heating element 15 which is made of resistance wire and is heated by an electric current which is supplied through the cables 16, 17 and 18. The circuit through the heating element as well as the motor in the casing 13 are controlled by the switch 19. The cable 21 is assumed to be a double cable and the switch 19 a double switch which simultaneously turns the current on in the motor and heating element. Adjacent to the heating element is the device 22 which may be either a rheostat or an ordinary switch for regulating the current in the heating element. If a rheostat is used the temperature of the discharged air may be regulated to any desired degree. 23 is a thermostatic element which is located in the top of the blower housing and is connected by conduit 24 to the thermostatic switch 25, the object of which is to automatically cut off the current flowing through the heating element in case the temperature should exceed a pre-determined point, say 120° F. As the thermostatic element and switch are well known standard equipment, detailed description is not deemed necessary. The stand 26 supports the entire unit and is preferably mounted on the rollers 27. Current for the unit is supplied through cable 28 which may be plugged into any convenient receptacle such as 29.

The mat 6 is preferably made of a plurality of coiled springs which are interlocked to hold them in position and I prefer to make the springs from 1 to 1½ inches in diameter and with wire of such size as provides sufficient strength to sustain the required weight and provide the desired resiliency.

40 Figure 2 is a fragmentary view showing some of the helical springs of the mat as seen along the line of the axis of said springs and the method by which they are interlocked. As indicated, each turn of wire engages an adjacent turn of the neighboring coil. A portion of the sheet 7 and section of the plaster cast 5 are indicated in this view.

The tubes 11 are preferably made of light material supported by an internal coiled spring to prevent them from kinking or collapsing. The middle tube 11 is provided with an extended sleeve 31 which telescopes through the collar 32 to provide a certain degree of adjustment in length to compensate for the various curves that may be made in the outer tubes when they are spread at various distances apart. Any number of tubes 11 and nozzles 9 may be used to carry out the principles of my invention, depending upon the size and requirements of the apparatus.

60 Referring to Figure 3 the coiled spring mat 6 is shown in plan view, no effort being made to illustrate the body of the patient in this view. Plate 10 is omitted in this figure. In Figure 3 the sheet 7 is partly broken away to show the spring mat 6 and position of the nozzles. This view also illustrates my method of preventing escape of the air currents through the edges of the mat. This is accomplished by threading a round strip of felt or wadding of any kind through the outer coil 70 of the mat as indicated by the numeral 33. If it is desired to use only a portion of the mat in cases where the cast may be shorter than the mat, the strip of wadding 33 may be threaded through any coil in the mat thus forming an effective 75 dam which confines the air currents to the de-

sired area, thus forcing them to circulate entirely around the body of the cast as indicated by the arrows in Figure 1. In Figure 3 the area indicated by the numeral 34 has one layer of the fabric of which the sheet is made removed to show the 5 position of the stays 8 which are held in place by the stitching 37.

Referring to Figure 4 a section of the tube 11 is broken away to show the coiled spring 38 and connection to the nozzle 9 and this view shows an enlarged view of the catch 39 which helps to hold the nozzles in operative position. This catch consists of a shank 41 which passes through openings in the angle pieces 42 and terminates in hook 43. A helical compression spring 44 bears 15 against the collar 45 which is fixed to the shank 41 and urges the shank towards its upward position as shown. When desired to remove the nozzle the latch 39 is pushed downwardly to disengage the hook 43 from the spring 6 so that the 20 nozzle may be changed in its position or removed entirely.

Figure 5 is a modified form of my invention in which the numeral 45 indicates a layer of canvas or other suitable fabric to which is secured by any 25 convenient means, such as stitching or cement, a plurality of strips of felt 46. In this view the numerals 47 indicate nozzles through which warm air is discharged and the numeral 5—a represents 30 a section of a plaster cast. In this figure the felt strips form the spacing element for which wire mat is used in Figures 1 and 3. In this modification the canvas and felt strips assembled together as shown constitute the mat.

When this modification is used the canvas 35 sheet is made sufficiently large to surround the cast and is placed so that the felt strips and the canvas form channels encircling the cast, and through which the warm air currents are conducted.

The modification shown in Figure 6 has the mat 6 and sheet 7 the same as shown in other views; but in this case another sheet 7a (preferably without stays) is placed on the upper side of the mat and the whole is held together by basting 45 them at intervals with a heavy thread 7b.

It should be understood that the mat 6 and the sheet 7 are preferably secured together at least at the outer edges, as for instance, by occasional stitches as indicated by the numeral 51, 50 as this enables the sheet with its stays 8 to maintain the mat always in a straight, convenient position for operation. However, these two parts may be separate units if desired.

The modus operandi is as follows: The mat and 55 its attendant sheet are spread on the bed with the mat 6 upward and the patient is then laid on the mat with the mat preferably extending throughout the entire length of the plaster cast. The nozzles are then latched into position as indicated in Figures 1, 3 and 4 and the mat and sheet are folded back over the patient to the position indicated in Figure 1. The switch 18 is then turned on and this simultaneously starts the motor and blower in operation and turns the current 60 through the heating elements 15. This starts a blast of warm air discharging through all of the nozzles, creating warm air currents which are somewhat diffused within the spaces of the mat and these encircle the patient and discharge from 70 under the sheet carrying with them moisture which is rapidly evaporated from the cast.

The nozzles, as will be noted from the drawing, do not need to cover the entire open end of the lower side of the mat but to promote even- 75

ness and rapidity in drying, the position of the nozzles may be changed from time to time.

It will be seen that the flexible mat and sheet conform nicely to the shape of the plaster cast for they cooperate with the springs of the bed which compress more in some places than in others, so that they maintain a perfect contact of the mat with the plaster cast on the lower side. On the upper side good contact is easily arranged by the attendant who carefully places the mat to conform to the shape of the cast. Thus it will be seen that the entire cast is dried simultaneously and without the necessity of moving the patient at all. The thermostatic element and switch 23 and 25 automatically cut off the current in the heater in the event that it should tend to become too hot for the comfort of the patient. This same action can be accomplished manually by means of switch or rheostat 22 if desired. In fact if the patient becomes uncomfortably warm the cool air which is forced through the mat when the current is turned off affords an excellent method of reducing the temperature in a very short time.

If desired, the same apparatus may be used either for warming or cooling a patient even in cases where a plaster cast is not involved, and it is within the spirit of the invention to so employ the apparatus for special therapeutic purposes. The modification shown in Figure 6 is especially adapted for this purpose, the mat, covered by a sheet on both sides being wrapped around the patient and air currents of the desired temperature are blown through the channels in the same manner as used for drying casts.

The apparatus herein described provides ideal conditions for rapidly drying plaster casts in that it supplies warmth and rapid means of carrying away the moist vapor and bringing fresh air in contact with the surfaces of the cast.

If extreme speed is essential desiccated air may be fed to the blower intake, but this is not ordinarily necessary.

While I have shown only the simplest form of sheet and mat it should be understood that various shapes may be used, such for instance as tubular ones to fit over the limbs.

Where the term sheet is used in the following claims it is intended to mean one or more layers of fabric or other material capable of forming a flexible wall to retain and guide the air currents in proper location to perform the functions described and it may or may not be supplied with stays or other stiffening means.

Where the terms "cast" or "plaster cast" may be used in the following claims it is intended to define a body of plaster of Paris or similar material used for supporting the limbs or other parts of the body after the setting of bones and for other surgical purposes. The plaster may or may not be reinforced by fabric or other material. These devices are referred to by some physicians as plaster cases.

Where the term "substantially impervious to air currents" is employed in this application it is intended to mean that the sheet of material is of sufficient density to retain the air currents in their desired locations even though the material has sufficient porosity to allow a certain amount of air to filter through it. For example muslin or light canvas is substantially impervious to air currents in the sense intended herein even though they are substantially porous to permit air under pressure to filter through them.

I claim:

1. An apparatus for drying plaster casts on the human body comprising a flexible mat made of a series of coiled springs having open spaces to permit free circulation of air currents, a sheet of flexible material substantially impervious to air currents on one side of said mat, conduit means for leading air currents from a blowing apparatus to the open spaces in said mat. 5

2. An apparatus for drying casts on the human body comprising a flexible mat consisting of a plurality of open interlocked resilient wire elements capable of supporting the body and cast without collapse and adapted to surround the body and cast with one open side of the mat directly contacting the cast, a flexible cover and deflector for the other side of the mat adapted to envelop the mat and cast, a blower for circulating a stream of air, heating means for warming the air stream circulated by the blower, and means for conducting the heated air stream from the blower into the mat in a direction substantially tangential to the surface of a cast. 10 15

3. A warming and drying apparatus comprising a flexible mat constructed of a plurality of coiled springs interlocked together with the axes of said springs in substantially parallel alignment and non-collapsible under the weight of the human body; air blowing means to force an air current through the passageways formed by the convolutions of said springs; air warming means associated with said blowing means; conduit means to convey the air from said blowing means to said passageways. 20 25

4. An apparatus for drying plaster casts on the human body comprising a flexible mat consisting of interlocked coil elements with open spaces for free circulation of air currents throughout the mat, said mat having its edges free and flexible and said interlocked elements being normally free from tension; the wire elements on one side of said mat comprising supporting members for direct contact with said plaster cast and providing open communication for passage of air from the mat to the surface of said cast; a flexible deflecting cover on the other side of the mat, 45 blower means for forcing air through the mat in direct contact with said cast; means for warming the air forced by said blower means; and conduit means connecting said blower and said mat. 50

5. The method of drying casts on the human body which comprises supporting the same in spaced relation to the reclining surface of a bed in direct contact with a plurality of open flexible interlocked metallic members forming a flexible mat capable of supporting the body and cast without collapse, and having substantially unrestricted passageways for air to allow diffusion of an air stream throughout the mat in direct contact with the body and cast, forcing a stream of air into the mat for diffusion therewithin, controlling the temperature of the air stream, and confining the air stream in passage through the mat and in contact with the body and cast by a flexible cover and deflector applied to the side of the mat opposite that in contact with the body and cast. 55 60 65

6. The method of drying casts on a human body which comprises supporting the body and cast in spaced relationship to the reclining face of a bed on one side of and in direct contact with a flexible mat of open interlocked wire elements having substantially unrestricted passageway for air to allow diffusion of an air stream throughout the mat and in contact with the body 70 75

and cast, covering the other side of the mat with a flexible cover and deflector and forcing a stream of air into the edge of the mat for diffusion therewith and in contact with said cast, and modifying the temperature of the air stream in its passage to the mat.

7. The method of drying casts on a human body which comprises supporting the body and cast in spaced relationship to the reclining surface of a bed on one side of and in direct contact

10 with a flexible mat of open interlocked wire elements having substantially unrestricted passageway for air to allow diffusion of an air stream throughout the mat and in contact with the body 15 and cast, directing a forced air stream underneath said cast and deflecting said current of air around the cast in a direction substantially parallel with the surface of said cast, whereby the air stream is caused to circulate substantially 20 around the entire cast to accelerate evaporation from the surface of the cast.

8. Means for circulating air currents underneath the body of a person in bed which comprises a flexible wire mat capable of sustaining 25 the weight of said person without collapse; said mat being formed of a plurality of symmetrical interlocked wire elements having the wires uniformly spaced to form continuous interconnected air passageways throughout the body of said mat; 30 blower means to project air currents into said air passageways and a heating element for warm-

ing the air currents projected by said blower; a conduit to lead said air currents from said blower to said mat; said conduit being exterior to and independent of said mat and terminating in a dispersing flared nozzle with its opening directed 5 toward the passageways in said mat whereby said air currents are immediately dispersed upon being discharged into said passageways for free and unrestricted circulation throughout the entire boundaries of said mat.

9. Means for circulating air currents underneath the body of a person in bed which comprises a flexible mat capable of sustaining the body of said person without collapse; said mat being formed of a plurality of helically coiled 15 interlocked metallic elements; the spaces within said coils forming a plurality of air passageways which extend continuously throughout the length of the mat; laterally interconnected passageways between the convolutions of said coils; means for 20 blowing air currents into all of said passageways; means for warming said air currents; conduit means for conducting said air currents from said blower means to said mat; said conduit terminating in a flared dispersing nozzle adjacent the 25 edge of said mat for discharging said air currents into said mat and causing them to disperse throughout said interconnecting passageways whereby warm air is diffused underneath the body of said person.

ERNEST J. SWEETLAND. 30
